(57) **CLAIM**

We claim the ornamental design for a folding reacher grabber, as shown and described.

DESCRIPTION

FIG. 1 is a perspective view of a folding reacher grabber showing my new design in a folded configuration of use; FIG. 2 is another perspective view of the folding reacher grabber as shown in FIG. 1; FIG. 3 is front view of the folding reacher grabber as shown in FIG. 1; FIG. 4 is back view of the folding reacher grabber as shown in FIG. 1; FIG. 5 is left-side view of the folding reacher grabber as shown in FIG. 1; and, FIG. 6 is a right-side view of the folding reacher grabber as shown in FIG. 1. No particular colour scheme forms part of the claimed design.
